UNITED STATES PATENT OFFICE.

ROY A. McCUNE, OF EAST PITTSBURGH, PENNSYLVANIA.

CAR PUSHER.

1,410,022.

Specification of Letters Patent. Patented Mar. 21, 1922.

Application filed January 17, 1921. Serial No. 437,775.

To all whom it may concern:

Be it known that I, ROY A. McCUNE, a citizen of the United States, and resident of East Pittsburgh, in the county of Allegheny 5 and State of Pennsylvania, have invented certain new and useful Improvements in Car Pushers, of which the following is a specification.

- My invention relates to manually operated 10 pushers for moving cars upon tracks, and has for one object the provision of an improved non-slip car pusher which is partly automatic in operation, and which will operate with great ease.
- Another object of the invention is the provision of a car pusher having a mechanically operated follow-up block or wedge adapted to engage the wheel of the car being moved, and prevent backward movement of the car.
- Another object of the invention is the provision of a car pusher having improved clamping means for holding the car pusher on the track.

These and other objects and advantages 25 will be more fully described in the following specification, and illustrated in the accompanying drawings, in which—

Figure 1 is a side elevation of the car pusher.

Figure 2 is a top plan of the pusher of Figure 1.

Figure 3 is a front elevation showing the clamps forming part of my improved apparatus in engagement with the head of a 35 track rail.

Figure 4 is a side elevation showing a modified form of apparatus embodying my invention.

Referring particularly to the drawings, 40 the numeral 2 designates the bed-plate or base of the car pusher which is adapted to ride on the top face of a track rail, and is provided with a pair of projecting ears 3 and 4, on the respective sides thereof, and 45 has a centrally arranged slot or groove 5 formed in its upper face and opening through the forward end.

A jaw member 6 is pivotally secured between each of the pairs of ears 3 and 4 by 50 a pivot or fulcrum pin 7 which passes through apertures in the ears and through a centrally arranged aperture in the jaw.

A slide bar 8 reduced in cross section from 55 a point adjacent its transverse center line rearward, to form a tongue portion 11, is slidably mounted within the slot or groove 5

in the bed-plate or base 2. The rear end of the tongue 11 is provided with a curved or convex bearing face 12, and is of greater vertical thickness than the main body of 60 the tongue, thereby providing a projection or locking lug 13 adapted to engage against a cross-bar 14 secured across the slot or groove 5 in the base 2 to prevent displacement of the bar 8.

The forward end of the slide bar 8 is recessed to receive a wedge block 9 pivotally held in position by a pin 10 which passes through the sides of the recessed portion of the bar 8 and through the block.

The jaws 6 are provided adjacent their upper ends with tapered bearing apertures 15 which are tapered toward their outer ends.

An operating lever 16 is mounted between 75 the upper ends of the jaws 6 and is pivotally held in position by a pivot or fulcrum pin 17 which passes through a bearing aperture in the lever, and through the tapered bearing apertures 15 in the jaws 6.

It will thus be seen that the lever 16 is pivotally supported on the jaws 6 by a pin 17, and that if pressure is applied to rock the lever downwardly, it will cause the jaws to rock on their pivots 7 in such a manner as 80 to force the lower ends of the jaws inwardly against the rail, and if the pressure be applied to lift the lever, the movement of the jaws will be reversed to move them away from the rails. This rocking movement of 85 the jaws is caused by the tapered form of the bearing aperture 15, which causes a wedging action when the pressure is applied to the lever 16 and pin 17.

The lever 16 projects rearwardly and upwardly on an angle from a point adjacent the bearing aperture for pivot 17, and has a handle socket member 18 pivotally mounted on its rear end for sidewise movement by a pivot pin 19 which passes through jaws 100 20-21 of the socket member 18 and through the end of the lever 16.

A pusher shoe 22 having a pair of projecting ears 23 on its rear side is pivotally mounted on the forward end of the lever 16 105 by a pin 24 which passes through apertures in the ears and an aperture in the lever. The face of the shoe 22 extends downwardly, forming a guide tongue 25 adapted to ride in a slot 26 in the slide bar 8.

The lever 16 is provided with a downwardly extending projection or lug 26 im-

mediately to the rear of the center line of the bearing 17, and is provided with a concave face 27 adapted to engage and ride on the convex face 12 of the tongue 11 of slide bar 8 when the lever is forced downwardly, thus forcing the slide bar 8 outward so as to force the wedge block under the wheel of the car being moved.

A second projection or lug 28 is provided adjacent the forward end of the lever 16 and has an inclined rear face 29 adapted to bear against the inclined rear face 30 of slot 26 in slide bar 8, as the lever 16 is raised, thus causing a wedging action. Before the lug 28 contacts with the face 30 of slot 26, the jaws 6 are released by the lifting of the lever 16, as explained before. Therefore, since the wedge block 9 is gripped under the car wheel, the wedging action caused by the face 29 of lugs 28 engaging the inclined face 30 of slot 26, will cause the bed-plate 2, lever 16, and jaws 6 to move forwardly relative to the slide bar 8, and thus be ready for a second contact with the car wheel.

The advantages of a device of this class where a simple swinging or rocking movement of the handle will automatically feed the device forward along the rail as the car is moved, will be readily seen by those skilled in the art.

The advantages of having an automatically operated pusher in which the parts are all composed of solid units, and the absence of springs or other easily broken elements will be readily appreciated, since the device must of necessity be capable of withstanding rough usage.

Attention is also directed to the arrangement of the handle socket 18, which is mounted for sidewise or lateral movement in order that the person using the device may stand either between or outside of the track rails as desired.

I claim:—

1. A car pusher comprising a base adapted to ride on the top face of a track rail, a pair of clamping jaws pivoted to said base and provided with tapered apertures adjacent their upper ends, an operating lever fulcrumed on a pin mounted in said apertures, a pusher shoe pivoted on the forward end of said lever, and a wedge member adapted to be moved forward by said lever to engage and hold the car wheel in moved position.

2. A car pusher comprising a base adapted to ride on the top face of a rail, a pair of clamping jaws pivoted to said base and provided with tapered apertures adjacent their upper ends, an operating lever fulcrumed on a pin mounted in said apertures, a pusher shoe pivoted on the forward end of said lever, a slide bar mounted for sliding movement in said base, a pivoted wedge block on the forward end of said slide bar, and means on said operating lever adapted to move said bar forward to engage and hold the car wheel in moved position.

3. A car pusher comprising in combination a base, a pair of clamping jaws, an operating lever, and a pusher shoe pivoted on the forward end of said lever, a slide bar mounted for sliding movement in said base, and means on said operating lever adapted to simultaneously move said bar forward as said pusher shoe engages the car wheel so as to cause said bar to engage and hold the car wheel in moved position.

4. A car pusher comprising in combination a base, a pair of clamping jaws, an operating lever, and a pusher shoe pivoted on the forward end of said lever, a slide bar mounted for sliding movement in said base, a pivoted wedge block on the forward end of said slide bar, and a projecting lug on said operating lever adapted to engage the rear end of said bar to simultaneously move said bar forward as said pusher shoe engages the car wheel so as to cause said wedge to engage and hold the car wheel in moved position.

5. The combination with a car pusher mover comprising in combination a base, a pair of clamping jaws, an operating lever, a pusher shoe pivoted on the forward end of said lever, a slide bar mounted for sliding movement in said base, a pivoted wedge block on the forward end of said slide bar, a projecting lug on said operating lever adapted to engage the rear end of said bar to simultaneously move said bar forward as said pusher shoe engages the car wheel so as to cause said wedge to engage and hold the car wheel in moved position, and means for automatically drawing said base, clamps, and operating lever forward after the termination of each pushing stroke.

In testimony whereof, I have hereunto signed my name.

ROY A. McCUNE,
